(57) **CLAIM**

The ornamental design for a female terminal, as shown and described.

DESCRIPTION

FIG. 1 is a top and front perspective view of a female terminal, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a top and front perspective view the female terminal in an alternate position.

The broken lines shown in FIGS. 1-8 are for illustrative purposes only and form no part of the claimed design.
